US00D590877S

(12) **United States Design Patent**
Ma

(10) **Patent No.:** **US D590,877 S**
(45) **Date of Patent:** **** Apr. 21, 2009**

(54) **HIGHLIGHTER**

(75) Inventor: **Lidan Ma**, Ningbo (CN)

(73) Assignee: **Beifa Group Co., Ltd.**, Ningbo (CN)

(**) Term: **14 Years**

(21) Appl. No.: **29/298,530**

(22) Filed: **Dec. 6, 2007**

(30) **Foreign Application Priority Data**

Jun. 6, 2007 (CN) 2007 3 0158204

(51) **LOC (9) Cl.** **19-06**

(52) **U.S. Cl.** **D19/43; D19/48**

(58) **Field of Classification Search** ..... D19/35, D19/36, 41, 42, 43, 44, 45, 46, 47, 48, 49, D19/50, 51, 54, 55, 56, 57; 24/11 F, 11 P, 24/11 R; 401/52, 99, 100, 104, 105, 106, 401/107, 108, 109, 192, 195, 196, 202, 209, 401/213, 243, 244, 245, 246, 247; 708/107

See application file for complete search history.

CLAIM

The ornamental design for a highlighter, as shown and described.

DESCRIPTION

FIG. 1 is an upper front right perspective view of a highlighter showing my new design;

FIG. 2 is an exploded upper front right perspective view thereof;

FIG. 3 is a right side elevation view of the highlighter shown in FIG. 1;

FIG. 4 is front elevation view thereof;

FIG. 5 is a left side elevation view thereof;

FIG. 6 is a rear elevation view thereof;

FIG. 7 is a top plan view thereof;

FIG. 8 is a bottom plan view thereof; and,

FIG. 9 is a front elevation view of the highlighter shown in FIG. 1 with the cap removed for convenience of illustration.

1 Claim, 4 Drawing Sheets
